UNITED STATES PATENT OFFICE.

SVERRE BENJAMIN HANSEN, OF BAYONNE, NEW JERSEY, AND NILS KRISTIAN ENOCH NILSEN, OF PORT RICHMOND, NEW YORK.

SAFETY GAS-BURNER.

1,234,018.

Specification of Letters Patent. Patented July 17, 1917.

Application filed December 4, 1916. Serial No. 134,946.

To all whom it may concern:

Be it known that we, SVERRE BENJAMIN HANSEN, a citizen of the United States, residing at Bayonne, Hudson county, and 5 State of New Jersey, and NILS KRISTIAN ENOCH NILSEN, a citizen of the United States, residing at Port Richmond, Richmond county, and State of New York, have invented and discovered certain new and 10 useful Improvements in Safety Gas-Burners, of which the following is a specification.

Our said invention relates to automatic cut-off devices for gas burners and consists in the combinations and arrangements of 15 elements hereinafter described and particularly set forth in the accompanying claims.

The invention has for its purpose to provide a device of this character which will positively operate to cut off the flow of gas 20 in the event that the flame should become accidentally extinguished, and which will in no manner interfere with the illumination when in applied position.

A further purpose of the invention is to 25 construct an automatic cut-off device for gas burners that may be readily fitted to present gas burners without requiring any alteration in the gas fixture, and which, when in applied position, will allow of the ordinary 30 use of the burner.

Another object of the invention is to provide a cut-off device that may be so mounted 35 on the gas fixture as to be conveniently swung clear thereof to the end that the gas mantel, or other equipment, may be fitted and adjusted after the ordinary manner.

The invention is shown by way of illustration in the accompanying drawings, wherein—

40 Figure 1 is a front elevation of the device in applied position, and showing the valve closed,

Fig. 2 a side view of the same, and

45 Fig. 3 a view similar to Fig. 1, showing the valve open.

Referring to the construction in further detail; the device consists of a suitable support comprising an arm 7 fitted to the pipe of the burner and supporting a block 8 to 50 one side of said pipe; and an upright supporting bar or rod 9 is fitted in said block through an aperture formed therein (see Fig. 3), and said bar has a pin 10 that en-

gages in a notch 11 at the upper end of the block for the purpose of holding the device 55 securely in operative position.

The bar 9 has its upper end portion 12 bent laterally, well within the heated zone of the flame, and said lateral portion has a thermostatic bar 13 secured to and depending therefrom, after the manner shown in Figs. 1 and 3. The two bars 9 and 13 pass through a suitable opening formed in the burner fixture B. The lower end of the rod 13 fits within an opening 14 of the block 65 8 and provides a latch that engages with the head 15 of a stud 16 carried by the lever 17, and which lever is secured to the turning plug or cock 18 of the gas burner. A spring 19 is fitted on the lower projecting 70 end 20 of the bar 9 and seats against the block 8 to hold the bar 13 in engagement with the stud 16, and said stud may be manually released by raising the bar 9 against the tension of the spring 19, when the latch 75 bar 13 will disengage said stud. The cock 18 is thereby held in open position, and a volute spring 21 is secured at its respective ends to the pipe of the burner, and the lever 17 normally tensions the latter to turn said 80 cock 18 and shut off the gas supply, as will be understood. The turning plug 18 is also provided with a bar forming members 22 and 23 for turning on the gas by hand and raising said lever to have the stud 16 there- 85 of engaged by the latch rod 13, and in which position the lever is held while the gas is burning.

It will be seen from the foregoing that the device as a whole may be conveniently 90 mounted on any gas fixture now in use without altering said fixture, and that the same is so designed that the illumination of the flame will not be interfered with; and it will be further evident that the device, when 95 in applied position, may be swung entirely clear of the burner for the purpose of adjusting the latter or fitting and removing the mantle therefrom.

It is obvious that those skilled in the art 100 may vary the details of construction and arrangement of parts without departing from the spirit of our invention, and therefore we do not wish to be limited to such features except as may be required by the 105 claims.

Having thus fully described our said invention, what we claim as new and desire to secure by Letters Patent, is:

1. An automatic cut-off device for gas burners comprising a suitable support, an upright bar mounted to have vertical movement on said support, a thermostatic bar depending from said upright bar and having the end thereof constructed to provide a latch, and a spring-tensioned arm adapted to be secured to the valve of the gas burner for holding said valve normally closed, said arm adapted to be held in open position by the latch end of said thermostatic bar and released thereby, and said upright bar adapted to be raised to manually release the latch, substantially as set forth.
2. An automatic cut-off device for gas burners comprising a suitable support having an aperture, a spring tensioned and upright bar mounted on said support, a thermostatic bar dependingly mounted on said upright bar and having the end thereof constructed to provide a latch, said latch engaging within the aperture of said support, a spring-tensioned arm adapted to be secured to the valve of the gas burner for holding said valve normally closed, and a member carried by said arm adapted to be engaged and held by said latch and released thereby, and said upright bar adapted to be raised to manually release the latch, substantially as set forth.
3. An automatic cut-off device for gas burners comprising a suitable support having a recess, an upright bar mounted on said support and constructed with an angular end portion, a thermostatic bar dependingly mounted on said end portion and fitting in the recess of said support providing a latch, a spring-tensioned arm adapted to be secured to the valve of the gas burner for holding said valve normally closed, and a

stud carried by said arm adapted to fit within said recess to be engaged and held by 45 said latch and released thereby, substantially as set forth.

4. An automatic cut-off device for gas burners comprising a supporting member having an aperture and a recess, a spring-tensioned upright bar fitting in said aperture, a thermostatic bar dependingly mounted on said upright bar and fitting within said recess providing a latch, a spring-tensioned arm adapted to be secured to the 55 valve of the gas burner for holding said valve normally closed, and a stud carried by said arm adapted to fit within said recess to be engaged and held by said latch and released thereby, substantially as set 60 forth.

5. An automatic cut-off device for gas burners comprising an arm adapted to be fitted on the pipe of the burner and having a suitable support provided with an aperture and a recess, a spring-tensioned upright bar fitting within the aperture of said support and having an angular end portion, a thermostatic bar dependingly mounted on the angular portion of said upright bar and having its lower end fitting in said recess providing a latch, a spring-tensioned arm adapted to be secured to the valve of the gas burner for holding said valve normally closed, and a stud carried by said arm adapted to be engaged and held by said latch and released thereby, substantially as set forth.

In witness whereof, we have hereunto set our hands and seals at Port Richmond, Richmond county, N. Y., this 27th day of November, A. D. nineteen hundred and sixteen.
